CLASP

Filed Feb. 13, 1930

*Inventor
Paul D. Smith
By his Attorneys
Merchant and Siegman*

UNITED STATES PATENT OFFICE

PAUL D. SMITH, OF MINNEAPOLIS, MINNESOTA

CLASP

Application filed February 13, 1930. Serial No. 423,063.

My invention has for its object to provide an extremely simple and highly efficient clasp adapted for general use but especially designed for use in connection with a catamenial appliance.

To the above end, generally stated, the invention consists of the novel construction and arrangement of parts hereinafter described and defined in the claims.

10 It is now the general practice to use a safety pin for attaching the casing of a sanitary pad to a sanitary belt, which is awkward and slow to operate particularly in the back, tends to bunch the pinned portion of the casing with a result that it may be noticeable through the outer garment, is very liable to tear the casing or tab of the belt, or both and thus mutilate and shorten the life of the belt. Furthermore, the handling of the tab while inserting a safety pin therethrough or the removal of the same therefrom very quickly soils the tab. If the pinning together of the casing and tab is not well done, the fastening is more or less insecure.

25 My invention provides a clasp without a movable part to be permanently attached to the tab of a sanitary belt. The clasp holds the attached portion of a casing spread out flat so that the same is very thin and it also holds 30 the loose end portion of the casing folded flat against the body of the wearer so that it is not noticeable through the outer garment. It also holds the casing in such a manner that it can not be pushed out of the clasp due to 35 friction with the other garments.

The improved clasp will securely hold the flat folded portion of a casing throughout its entire width with the same pressure so that it will not slip and tend to work to one side 40 of the clasp and thereby bunch. The peculiar formation of the clasp is such that a casing may be very easily and quickly attached thereto or detached therefrom either at the front or the back without any inconvenience or 45 effort.

In the accompanying drawings, which illustrate the invention, like characters indicate like parts throughout the several views.

50 Referring to the drawings:

Fig. 1 is a fragmentary view of a catame-

nial appliance to which the improved clasp is applied;

Fig. 2 is a view partly in edge elevation and partly in section taken on the line 2—2 of Fig. 1;

Fig. 3 is a view in transverse section taken on the line 3—3 of Fig. 1; and

Fig. 4 is a fragmentary view of a belt tab to which another form of the improved clasp is attached.

The catamenial appliance illustrated and in which the improved clasp is embodied, includes a sanitary belt 5 having front and rear depending tabs 6, only the former of which is shown, and the casing 7 of a sanitary pad.

Referring first to the improved clasp 8, as shown in Figs. 1, 2 and 3, the same is formed from a single flat sheet of spring metal, has the same general contour as a hook and comprises a body 9, a finger 10 formed with said body and spaced therefrom to leave a long narrow oblique slot 11 therebetween with parallel sides, and a guard 12.

The clasp 8 is held in an upright position, as will hereinafter appear. The end of the finger 10 extends outward of and above the upper end of the body 9 and which end and the adjacent portion of the body 9 are in diverging relation to form an entrance passageway 13 to the slot 11. The guard 12 extends materially above the upper end of the body 9 as well as the end of the finger 10 and has formed therein a transversely elongated eye 14. A short strap 15 extends through the eye 14, is stitched to the tab 6 and holds the clasp 8 suspended from the tab. The end of the finger 10 and upper end portion of the guard 12 are in diverging relation to form an entrance passageway 16 therebetween.

The guard 12 is formed with the back edge of the body 9, overlies said body, slot 11 and adjacent portion of the finger 10. Said guard 12 terminates short of the lower end of the body 9 and the body 9 below the guard 12 is provided with an eye 17. The lower end of the clasp 8 is secured to the tab 6 by stitches 18 passed through said tab and eye 17. By reference to Fig. 1, it will be noted that the attachment of the clasp 8

100

by the strap 15 and stitches 18 is such that said clasp at the finger 10 may be turned away from the tab 15 to facilitate the attachment of the casing 7 to the clasp 8. The 5 finger 10 is transversely bulged toward the guard 12 so that the overlying edge of said guard is relatively closed thereto and the guard 12 is transversely bulged from the body 9, see Fig. 3.

10 To attach the casing 7 to the tab 6 by the clasp 8 said casing is folded, as shown in Fig. 1, and the clasp 8 turned away from the tab 6 to space the finger 10 therefrom. While the casing 7 and clasp 8 are thus held said 15 casing is placed in the entrance passageway 16, and a downward pull thereon will direct the slot 11 with the loose end portion of said casing between the finger 10 and guard 12.

The narrow slot 11 holds the casing 7 20 transversely smooth and pinched tight between the parallel sides of the slot 11 throughout its full width with equal pressure so that the same will not slip longitudinally or transversely into the lower end of the slot 11 and 25 thereby bunch. That part of the guard 12 overlying the slot 11 causes the loose end of the casing 7 to be folded over and lie flat against the tab.

The proximity of the finger 10 and guard 30 12 is such that the same are slightly separated by the insertion of the casing 7 therebetween so that there is a slight pinching spring action on the casing. The flat structure of the clasp 8 and the manner in which it holds 35 the casing 7 keep the connected parts of the appliance smooth so that there are no raised or bumping surfaces therein. It is also evident that the casing 7 may be easily and quickly attached to or released from the clasp 40 8 and the attachment of the casing 7 to the clasp 8 automatically folds the free end of the casing 7 laterally as shown by its entrance between the finger 10 and guard 12. The slightly raised or bulged surfaces of the 45 finger 10 and guard 12 gives the clasp 8 a neat and pleasing finish, makes the casing 7 operate more smoothly in the slot 11 and increases the rigidity thereof.

Referring now to the structure shown in 50 Fig. 4, the clasp 19 is substantially the same as the clasp 8 except the guard is dispensed with and the body 20 is sewed directly to the tab 21 by stitches 22 passed through said tab and upper and lower eyes 23 in said body.

55 What I claim is:

1. A clasp having the general contour of a hook and comprising a body, and a finger connected to the body and spaced therefrom to leave therebetween a narrow oblique slot 60 having parallel sides, said clasp having an eye at each extremity through which fastening means may be inserted to attach the clasp to an article, said eyes being back of the slot to permit the clasp at the finger to be 65 turned from the article to which the clasp

is attached for the insertion of a member in the slot.

2. The structure defined in claim 1 in which the end of the finger and the adjacent extremity of the body are in diverging relation to form an entrance passageway to the 70 slot.

3. The combination with an article, of a clasp having the general contour of a hook and comprising a body, a finger connected to the body and spaced therefrom to leave therebetween a narrow oblique slot having parallel sides, the end of the finger being outward of the adjacent extremity of the body, said extremity and body being in diverging relation to form an entrance passageway to the slot, said clasp having at one extremity an eye, and a short strap inserted through said eye and connecting the clasp to the article, said clasp also having at 80 its other extremity an eye and which extremity is secured to the article by stitches passed through the respective eye.

4. A clasp having the general contour of a hook and comprising a body, a finger connected to the body and spaced therefrom to leave therebetween a narrow oblique slot, and a guard on the body overlying the slot and having an eye.

5. A clasp having the general contour of a hook and comprising a body, a finger connected to the body and spaced therefrom to leave therebetween a narrow oblique slot, and a guard on the body overlying the slot, extending outward of the body at the entrance of the slot and having an eye.

6. The structure defined in claim 5 in which the guard terminates short of the end of the body to which the finger is connected and in which end of the body is an eye.

7. A clasp having the general contour of a hook and comprising a body, a finger connected to the body at the front thereof and spaced therefrom to leave therebetween a narrow oblique slot, and a guard formed with the body at its back, overlying the body, slot and the finger at the slot and laterally spaced from said body and finger, said guard being extended outward of the body at the entrance of the slot and having an eye therein.

8. The structure defined in claim 7 in which the guard is transversely outwardly bulged from the body.

9. The structure defined in claim 7 in which the guard is transversely outwardly bulged from the body and in which the finger is transversely outwardly bulged toward the guard.

10. The structure defined in claim 7 in which the guard terminates short of the end of the body to which the finger is connected and in which end of the body is an eye outward of the guard.

11. The structure defined in claim 7 in

which the end of the finger projects outward of the guard and in which said guard and end of the finger are in diverging relation.

12. The structure defined in claim 7 in which the end of the finger and the adjacent extremity of the body are in diverging relation to form an entrance passageway to the slot and in which the end of the finger and adjacent portion of the guard are in diverging relation.

13. The combination with an article, of a clasp having the general contour of a hook and comprising a body, a finger connected to the body and spaced therefrom to leave therebetween a narrow oblique slot, the end of the finger being outward of the adjacent extremity of the body, said extremity and body being in diverging relation to form an entrance passageway to the slot, and a guard formed with the body, overlying said body, slot and adjacent portion of the finger, the end of the finger and adjacent portion of the guard being in diverging relation, the extremity of the guard at the end of the finger being extended outward of the body and having an eye, and a short strap inserted through said eye and connecting the clasp to the article, the other extremity of the guard terminating short of the adjacent end of the body, said end of the body having an eye outward of the guard and secured to the article by stitches passed through the respective eye.

35 In testimony whereof I affix my signature.
PAUL D. SMITH.
